UNITED STATES PATENT OFFICE.

ELBERT W. BARTON, OF BINGHAMTON, NEW YORK.

MECHANICAL TOY.

1,286,915.

Specification of Letters Patent. Patented Dec. 10, 1918.

Application filed October 23, 1917. Serial No. 198,065.

To all whom it may concern:

Be it known that I, ELBERT W. BARTON, a citizen of the United States, residing at Binghamton, in the county of Broome and State of New York, have invented certain new and useful Improvements in Mechanical Toys, of which the following is a specification.

This invention has relation to mechanical 10 toys, and has for an object to provide a toy having a peculiar mechanical movement which will prove of interest to an operator, and which will instruct the young in the principles of mechanics.

15 Another object of the invention is to provide a mechanical movement which by giving a slight initial impetus, will run for some time without additional impetus, and will be of interest and amusement, owing to 20 the peculiar movements of some of the parts of the toy.

In addition to the foregoing, this invention comprehends improvements in the details of construction and arrangement of 25 parts, to be hereinafter described and particularly pointed out in the appended claims.

In the accompanying drawings, in which similar and corresponding parts are designated by the same characters of reference 30 throughout the several views in which they appear:

Figure 1 is a view in side elevation of a mechanical toy constructed in accordance with my invention.

35 Fig. 2 is a view thereof in vertical section, and

Fig. 3 is a detail section taken on the line 3—3 of Fig. 1.

With reference to the drawings, 1 designates the base, and 2 the vertical supports bolted to the base and provided with a cross head 3 at the upper end thereof, said cross head being connected to the uprights by means of bolts 4. Crossed braces 5 extend 45 from one of the uprights to the other and are secured thereto by bolts.

Mounted in suitable bearing brackets 6 supported upon the base 1 is a shaft 7 provided with a belt pulley 8 and a fly wheel 9. 50 Near the opposite ends of the shaft 7 and properly keyed to said shaft are tapped wheels 10 provided with a series of radial spokes 11, each having a resilient ball 12 secured to the end thereof. As shown, there 55 are four of these spokes, each provided with

a resilient ball, but it will be understood that any number may be utilized.

Depending from the cross head 3 are the bearing brackets 13 secured underneath said cross head by means of suitable bolts 14. 60 Mounted in said brackets is a shaft 15. Keyed to said shaft is a belt pulley 16 and a belt 17 extends around said pulley 16 and around the belt pulley 8 on said shaft 7. The shaft 15 extends beyond the frame of 65 the toy and near the outer ends of the said shaft are keyed the power wheels 18. Upon the opposite sides of each of the wheels 18 is a clutch comprising a plate 19 having an enlarged portion 20, said plate being connected to a bearing block by means of bolts 22. The blocks 21 are provided with inclined inner surfaces 23, while their outer edges 24 bear slightly against the sides of the rim of the wheel 18. In the space formed by the 70 inclined or cut away portion 23 of the blocks 21 are mounted springs 25 secured to the plates 19, while at the outer ends of the springs 25 rollers 26 are mounted. Secured between the plates 19 at opposite sides of 75 each wheel is a tappet arm 27, said arm being connected to the plates 19 by suitable bolts 28. The lower ends of the tappet arms 27 are in the path of the tappet balls 12. It is to be noted that the tappet arms 27 are 80 disposed upon opposite sides of the wheels 18, so that when one is exerting its weight to rotate the wheel in the direction of the arrow shown in Fig. 1, the other tappet arm has 85 been struck by one of the tappet balls and is 90 passed upward. Secured to the shaft 7 is a crank 29, this crank may be used or not as desired.

In operation, the fly wheel 9 is given a slight rotative impetus and rotation of the 95 shaft 7 is transmitted through the pulleys 8 and 16 and belt 17 to the shaft 15. One or the other of the tappet arms 27 will be engaged by one of the balls 12 of a corresponding tappet wheel 10 the effect of which is to 100 throw the arm upward, the arms being alternately struck by the tappet balls. At each upward movement of either of the arms 27 the clutches carried by the arms will operate to engage the wheels 18 so as to carry said 105 wheels around for a partial revolution. The motion of said wheels 18 will be then transmitted through the belt 17 and pulleys 8 and 16 to the shaft 7, rotating the same. The machine in operation will then have the 110

appearance of operating without the application of external power. Motion of the machine will however cease when the inertia of the moving parts is overcome. Operation 5 of the machine may be continued indefinitely by rotating the crank 29.

While I have illustrated and described my invention with some degree of particularity, I realize that in practice various alterations 10 therein may be made. I therefore reserve the right and privilege of changing the form of the details of construction, or otherwise altering the arrangement of the correlated parts, without departing from the spirit of 15 the invention or the scope of the appended claims.

Having thus described my invention, what I claim as new and desire to secure by Letters Patent is:

- 20 1. A mechanical toy comprising a drive shaft having a series of tappet arms connected thereto and rotatable therewith, a driven shaft provided with a pair of wheels keyed thereto, tappet arms connected to said driven shaft and extended beyond the peripheries of said wheels, said shafts being connected by a driving belt, a crank to rotate said drive shaft, and to operate the tappet 25 wheels to strike said tappet arms, and clutches for said tappet arms, said clutches 30 adapted to engage the rims of the wheels on the driven shaft during the downward movement of each of the tappet arms.
- 35 2. A mechanical toy comprising a frame, a drive shaft, tappet wheels on said drive shaft, resilient tappet balls at the ends of the spokes of said tappet wheels, a driven shaft, a belt connecting said driven shaft with said drive shaft, power wheels on said driven 40 shaft, tappet arms connected to said shaft

Copies of this patent may be obtained for five cents each, by addressing the "Commissioner of Patents, Washington, D. C."

and extending beyond the peripheries of said wheels into the path of said tappet wheels, clutches to engage said wheels during the downward movement of said tappet arms, and means for rotating the drive shaft. 45

3. A mechanical toy comprising a frame, a drive shaft, a driven shaft, connections between said shafts, tappet wheels on the drive shaft, tappet arms carried by the driven shaft, drive wheels, clutches to engage said 50 wheels during the downward movement of the tappet arms, and means for rotating the drive shaft.

4. In a mechanical toy, the combination of a drive shaft, tappet wheels at the opposite 55 ends of said drive shaft, said wheels comprising spokes having resilient tappet balls at the ends thereof, a driven shaft, connections between said driven shaft and drive shaft, wheels on said driven shaft, tappet 60 arms connected to said shaft and provided with oppositely disposed clutch members to engage the sides of the wheels during the downward movement of each of the tappet arms, and means for giving an initial impetus to the drive shaft. 65

5. A mechanical toy comprising a drive shaft, a driven shaft, pulleys on said shafts, a belt on said pulleys connecting said shafts, oppositely positioned tappet arms connected 70 to said driven shaft, clutches connected to said arms, each clutch comprising a plate, bearing blocks secured to said plate, and means to rotate said drive shaft. 75

In testimony whereof I affix my signature in the presence of two witnesses.

ELBERT W. BARTON.
